UNITED STATES PATENT OFFICE.

GALEN TILDEN, OF AMES, IOWA.

CALENDAR STRUCTURE.

Application filed June 5, 1926. Serial No. 114,016.

The object of my invention is to provide a calendar structure of simple, durable and inexpensive construction.

A further object is to provide a calendar structure or similar article having dials or the like thereon which have indicating numbers to be exposed through openings in the front of the device.

Still a further object is to provide some of the dials in such a device mounted in front of other ones whereby space is conserved and the device is made as small as is practical considering the kind of indicating characters required on the dials.

Still a further object is to provide a means whereby the indicating characters on both the top and bottom dials are exposed to view at the front of the device without interfering with each other.

With these and other objects in view, my invention consists in the construction, arrangement and combination of the various parts of my calendar structure, whereby the objects contemplated are attained, as herein-after more fully set forth, pointed out in my claims, and illustrated in the accompanying drawings, in which:

Figure 1 is a front elevation of a calendar embodying my invention.

Figure 2 is a rear elevation thereof.

Figure 3 is a front elevation of the device with the front cover removed; and

Figure 4 is an elevation similar to Figure 3 with the front disk removed.

I have illustrated my device in connection with a calendar, the back of which is indicated by the reference numeral 10 and forms a support for the remaining parts.

Rotatably secured to the back 10 are disks 11 and 12. For securing the disks 11 and 12 to the back 10, I employ tubular rivets or the like 13. The dials 11 and 12 are used for the purpose of determining the proper calendars to use for any given month of any given year and are not essentially a part of this invention.

The indicating characters on them are exposed through slots 14 in the back 10. Overlying the dials 11 and 12 is a larger dial 15 rotatably secured to the back 10 by a tubular rivet 16. The dial 15 when used in connection with a calendar, has a set of calendars 17 on its front side. Each calendar is given a number 18 which indicates which day of the week the month indicated by that calendar begins on. Any one of the calendars 17 may

be exposed to view through the front 19 of the calendar. To accomplish this result I provide a sight opening 20 which is substantially the shape of a calendar printed on the disk 15.

In designing a calendar or the like, it is desirable to condense the dials of the structure whereby a small calendar is the result. This may be accomplished by arranging certain of the dials to overlie others such as the dials 15 overlying the dials 11 and 12. A fourth dial 21 is provided and rotatably secured to the back 10 by a tubular rivet 22. It will be noted that the dial 15 also overlies the dial 21 in order to conserve space. By thus over-lapping the dials 15 and 21, the problem of exposing the indicating characters on the dial 21 through a slot 23 in the front 19 of the calendar is encountered.

It may here be mentioned that the indicating characters on the dial 21 consist of the names of the months and the number of days thereof as indicated by the reference numeral 24.

In order to render the indicating characters 24 visible through the opening 23, I provide an opening 25 in the disk 15 of substantially the same shape as the opening 23 and which registers therewith when any calendar 17 is exposed through the opening 20. It will be noted that there is an opening 25 corresponding to each calendar 17 whereby the disk 15 in any of its proper adjusted positions will allow a portion of the disk 21 to be exposed through the opening 23. In order to allow manipulation of the disks 11, 12, 15, and 21, I provide cut-away portions 26, 27, and 28 of the back 10. The front 19 is suitably secured to the back 10 by rivets or the like 29 whereby the tubular rivets 13, 16, and 22 are concealed. It will be obvious that this device need not be limited to one having rotating disks but would answer as well in a device having sliding parts with indicating characters thereon in which certain of said sliding parts overlie others.

Having thus described my invention, it will be seen that I have provided a means whereby indicating characters on certain disks or the like will be exposed to view through openings in the disk overlying them when the overlying disk is in any of its predetermined adjusted positions.

Some changes may be made in the details of the construction and arrangement of the parts of my calendar structure and it is my

intention to cover by the claims of the patent to be issued upon my application, any modified forms of structure or use of mechanical equivalents, which may be reasonably included within their scope.

I claim as my invention:

1. In a device of the class described, a support, a pair of sight openings therein, a movable member having sets of characters thereon for being selectively exposed through one of said sight openings, a sight opening in said member for each set of characters, each one being positioned relative to its corresponding set of characters whereby it will be in alignment with the other sight opening in said support when its corresponding set of characters is exposed through the first sight opening and a second movable member having sets of indicating characters adapted to be selectively exposed through the aligned sight openings in said support independent of the first movable member.
2. In a device of the class described, a support, a disk mounted for rotation on said support and having a series of seven sight open-

ings arranged in a circle, calendars for months commencing on the respective different days of the week radially opposite the respective sight openings, a cover for said disk having two sight openings and having adjacent to one of said sight openings characters indicating the days of the week whereby by the rotation of the disk any set of characters on the disk may be selectively made visible, a second disk rotatably mounted on said support underlying the first disk, a series of sets of characters arranged in a circle around said second disk each set representing a month, the structure of the parts being such that when any set of characters on the first disk is exposed through one of the sight openings in the support, one of the sight openings in the first disk is in alignment with the other sight opening in the support whereby there is visible through the aligned sight openings one of the sets of characters on the second disk.

Des Moines, Iowa, June 1, 1926.

GALEN TILDEN.
